UNITED STATES PATENT OFFICE.

VICTOR H. PALM, OF BUTLER, PENNSYLVANIA, ASSIGNOR TO T. W. PHILLIPS MANUFACTURING COMPANY, OF BUTLER, PENNSYLVANIA, A CORPORATION OF PENNSYLVANIA.

SAND PUMP AND BAIL.

No. 880,462.

Specification of Letters Patent.

Patented Feb. 25, 1908.

Application filed April 19, 1907. Serial No. 369,066.

To all whom it may concern:

Be it known that I, VICTOR H. PALM, a citizen of the United States of America, residing at Butler, in the county of Butler and State of Pennsylvania, have invented certain new and useful Improvements in Sand Pumps and Bails, of which the following is a specification, reference being had therein to the accompanying drawing.

10 This invention relates to sand pumps and bails, and the invention has for its object the provision of positive and reliable means for detachably holding a head or bail in a sand pump.

15 My invention aims to provide a novel attachment for the present type of sand pump commonly used in oil well districts, and in this connection, I have aimed to dispense with the time and labor heretofore incurred 20 when emptying or removing sand from a pump. To this end, I have devised a detachable head for a sand pump and a plurality of resilient arms for normally holding the head in engagement with the pump body, 25 the head being constructed whereby it can be rotated and locked in engagement with the resilient arms.

My invention is also applicable to the ordinary bail used in connection with an oil 30 or Artesian well, the invention being designed for retaining a bail in the body of a sand pump, whereby the sand pump can be either used for pumping sand or in connection with a bail.

35 The detail construction entering into my invention will be hereinafter more fully described and then specifically pointed out in the appended claims, and referring to the drawing forming part of this specification, like numerals of reference designate corresponding parts throughout the several views, in which:—

Figure 1 is a fragmentary elevation of a sand pump constructed in accordance with 45 my invention. Fig. 2 is an end view of the same. Fig. 3 is a longitudinal sectional view of the sand pump. Fig. 4 is an elevation of a wrench particularly designed for my improvement, Fig. 5 is a longitudinal sectional view of the bail constructed in accordance with my invention. Fig. 6 is a perspective view of one of the resilient arms of my improvement.

In the accompanying drawing, I have 55 illustrated an ordinary sand pump consisting

of a cylindrical body 1 having a spring held plunger 2 arranged in one end thereof. In the opposite end of the cylindrical body 1 detachably mount a head 3, said head being carried by a sleeve 4 having an annular collar 5 adapted to abut against the end of the cylindrical body portion 1, and an annular groove 6. The end of the sleeve 4 fitting within the cylindrical body portion 1 of the sand pump is provided with a conventional 65 form of flap valve 7 commonly used in connection with sand pumps.

The cylindrical body portion 1 of the sand pump is provided with three equally spaced recesses 8 in which are secured the ends of 70 resilient arms 9, the outer ends of said arms being provided with blocks 10 having beveled faces 11.

The head 3 of the sleeve 4 is provided with three equally spaced slots 12 and adjacent to the groove 6 is recessed to provide seats 14 for the blocks 10 beneath the overhanging lugs 15 of the head 3, said lugs being formed when the head is slotted and recessed, as just described.

In Fig. 4 of the drawing, I have illustrated a wrench which I have designed particularly for my improvement, the wrench being of that type commonly known as a spanner wrench. The head 16 of the wrench is cut 85 away to provide curved surfaces 17 terminating in shoulders 18. When it is desired to place the head 3 in engagement with the cylindrical body portion 1 of the sand pump, the wrench is placed over the body portion 1 90 and rotated until the curved surfaces 17 of the wrench engage the resilient arms and press said arms inwardly, causing the blocks to recede into the annular groove 6. The head 3 can then be rotated until the overhanging lugs 15 pass over the outer edges of the blocks 10 at which time by removing the wrench or slightly rotating the same, the blocks 10 will recede into the seats 14 provided therefor. It will thus be impossible 100 for the head 3 to become detached from the cylindrical body portion 1 of the sand pump, as the rear ends 19 of the blocks 10 engage the collar 5 of the sleeve 4, and it will be equally impossible for the head to rotate, 105 until the resilient arms 9 are pressed inwardly, it being almost impossible to accomplish this unless a suitable wrench is employed.

In Fig. 5 of the drawing, I have illustrated 110

a cylindrical body 20 of a bail, and I provide the forward end of the body 20 with an annular groove 6, slots 12 and seats 14 similar to the head 3, whereby the cylindrical body 5 20 of the bail can be slipped into the cylindrical body 1 of the sand pump and locked therein by the resilient arms 9.

From the foregoing description taken in connection with the drawing, it will be observed that I have devised simple and inexpensive means for retaining a detachable head or bail in engagement with the cylindrical body portion of a sand pump, and it is thought that the operation and general usefulness of my invention will be apparent to those familiar with oil well devices, without further illustration or description. I desire it to be understood that such changes in the size, proportion and minor details of 15 construction, as are permissible by the appended claims, may be resorted to without departing from the spirit and scope of the invention.

What I claim and desire to secure by Letters Patent, is:—

1. The combination with a sand pump having a cylindrical body, of a sleeve adapted

to fit therein, a collar carried by said sleeve and adapted to engage said body, said sleeve having an annular groove formed therein, a 30 head carried by said sleeve and having slots formed therein providing projecting lugs, resilient arms secured to said body, blocks carried by the ends of said arms and adapted to engage in said annular recess, and the 35 slots of said head, and means to hold said arms beneath said overhanging lugs.

2. The combination with a sand pump having a cylindrical body, of a sleeve adapted to fit therein, a collar carried by said sleeve 40 and engaging the end of said body, a head carried by said sleeve, overhanging lugs carried by said head and having recesses formed therein, resilient arms carried by said body, blocks fixed upon the ends of said arms and 45 adapted to seat in said overhanging lugs and engage said collar.

In testimony whereof I affix my signature in the presence of two witnesses.

VICTOR H. PALM.
